Del., a corporation of Delaware

Original application October 5, 1933, Serial No.
692,236. Divided and this application Decem-
ber 25, 1934, Serial No. 759,129

31 Claims. (Cl. 60—105)

This invention relates to high speed steam and power producing apparatus.

This application is a divisional of my application Serial No. 692,236, filed Oct. 5, 1933.

5 The steam generating apparatus in accordance with the present invention comprehends semi-unidirectional flow of the main working fluid in my steam generating elements under conditions of high temperature radiant and convection heat transfer at high rates of heat release.

10 A main object of my invention is to reduce the size, weight, and cost of high speed steam producing apparatus and high speed steam power plants. I do this by increasing their speed of operation.

15 It is vital that the main working fluid especially, flow at least semi-unidirectionally at all times, under all steam making loads and speeds, substantially regardless of firebox temperatures or rates of heat release.

20 It is the object of the present invention to provide a rugged and compact steam generating apparatus having a combustion chamber and additional gas passages therearound with the tubes 25 conducting the fluids and mixtures thereof arranged therein in such a way as to effectuate a most efficient extraction of the heat energy under extremely rapid rates of heat generation and energy transference to the fluids undergoing rapid circulation.

30 It is a further object of the invention to provide a steam generating apparatus characterized by a control and coordination of the combustion gases and the fluids heated thereby to obtain a unit of maximum safety and efficiency.

35 It is a further object of my invention to provide an efficient and compact power plant embodying a steam generator in accordance with the present invention.

40 A prime object of the present invention is to increase the speed of steam generation and power production, thus making my steam generating apparatus and my steam power plant smaller, lighter weight, and less expensive.

45 This present invention is particularly concerned with the improvement of high speed steam boilers, and power plants embodying the same. Where my invention, and/or any of its features, applies to flash boilers and to high speed

50 power plants using said flash boilers, such improvements are well within the scope of my invention as herein described.

55 While my invention has been described herein as relating to steam generating apparatus and is intended especially for the generation of steam

from water, it will be understood that the terms "steam" and "water" as used in the specifications and claims are intended to include as equivalents, any liquids which might be handled by the novel apparatus herein described, resulting in the generation of any vapors which might be handled by or be useful in connection with my apparatus, and it will also be understood that many of the novel features of this invention are applicable in other fields than that for which the apparatus 10 herein specifically illustrated and described is particularly intended.

An important object of this invention is to coordinate the quantity of liquid used in forced circulation with pressure drop devices in the steam generating tubes in order to obtain positive input of water into each tube in sufficient quantity to protect each tube regardless of how rapid rates of heat release are obtained in the combustion chamber, up to the maximum heat effects 20 for which said (combustion chamber) is designed to withstand; and to show and describe how the flow of steam and water within and throughout the length of the tubes can also always be semi-unidirectionally uniform under any 25 combustion chamber heat releasing conditions for which they are designed.

Since this invention is concerned directly with steam making apparatus for producing steam rapidly, and with methods of operating such apparatus using high speed equipment for the production of power, the separate and correlated inter-acting mechanical features and combinations by which all of these above objects are attained, and their close inter-relation and inter-dependence in securing high speeds in steam generation, and steam power production, (which are among the main objects of this invention), are made possible, in certain instances, by the creation of new devices and methods of making and 30 using said devices.

35 Other objects and features will be particularly pointed out and disclosed hereinafter in the illustrations, descriptions, specifications and claims of this present patent application.

40 In the drawings:

ufacture, whereby the heat transfer fins are thinned and lengthened to obtain added heat exchanging effect.

In Figure 1 of the drawings is shown the power plant including as a part thereof, a steam generator adapted to produce steam of high energy content, in accordance with the present invention. The steam generator is designated by 1, having a plurality of steam generator water wall tubes 34 therein receiving water from the water wall inlet header 33, and discharging water and/or steam to the steam generator outlet water wall collecting header 36. These tubes are exposed to a source of radiant heat produced by a flame fed with fuel from burner 2 in the burner throat 3. The combustion of the fuel oil is assisted by a source of air which may be supplied from the super-charger 5, to which air is admitted through inlet 41, feeding air through the discharge lead 4 to the burner throat. The steam generator tubes are shown fitted with pressure drop devices 35, for controlling the input of water into each tube in sufficient quantity to protect the tube and to control the flow of steam and water in each tube to insure the proper operation thereof, said pressure drop devices being placed in an intermediate portion of the length of each tube, in accordance with the present invention. These devices are shown in greater detail in Figures 3 and 4.

In accordance with my invention, the placing of pressure drop devices beyond the water inlet end of the tubes, or in that part of the tube exposed to radiant and/or convection heat, is a preferred position for these pressure drop devices, or orifices, if orifices are used as pressure drop devices.

Also, in accordance with my invention, the pressure drop devices are placed preferably at any point in the tube beyond the point where steam begins to form, at the designed rate of heat release for the steam generator, thus insuring under the proper load conditions, the passing through the pressure drop device of at least some steam with the water.

This immediately gives the advantage of a larger area for steam and water passage through the pressure drop device for a given pressure drop, and a given quantity of water, than would be possible if water alone were passed through the pressure drop device.

This new position of my pressure drop device is also of immediate advantage to reduce the possibility of clogging, whether the steam generator is used, as in my present invention, operating a part of the steam generating tube with a so-called full tube condition, or if the heat release permits, and it is desirable to operate a part of the steam generator under conditions of my previous inventions using less than enough water than is normally required to fill the tube.

However, the most desirable position of my pressure drop device is at that position of the length of the tube which at the maximum rates of heat release for which it is designed will insure a sufficient length of the tube to give unidirectional flow of the working fluid so that the steam generator operating as a whole will not have serious steam and water surging conditions caused by that part of the tube in which unidirectional flow is not insured.

By advancing the orifice toward the outlet end of the tube, as in the present invention, the proportion of the length of the tube behind

- the orifice which has a compact column of steam and water, increases; and the proportion of length past the orifice toward the outlet end, which is subject to the surging action, decreases; 5 reducing the degree of interference to proper steam making operation from back and forth flow or surging flow. The tube under this condition has an assured unidirectional flow for that part of its length between the orifice and 10 the inlet end, while the part of the length from the orifice to the outlet end may have some degree of surging or non-unidirectional flow. This results in the tube as a whole giving what is termed semi-unidirectional flow.
- 15 As the rate of heat release increases, the need of advancing the orifice along the tube, toward the outlet end of the tube, likewise increases, until the exit end of the tube is finally reached. This is further discussed in my co-pending application Serial No. 686,268.

The selection of the point along the length of the tube where the orifice can best be used is a matter of the general duty for which the apparatus is designed and for which it is to be 25 put in use. The main factors to be considered are—

1. The rate of heat release in the combustion zone.
2. The degree of fluid compactness required 30 to prevent surging in the hydraulic column from behind the orifice to the inlet end of the steam generating tube.
3. The degree of fluid compactness required to prevent surging in the hydraulic column from 35 immediately beyond the orifice to the outlet end of the steam generating tube, in which some surging can be permitted without interfering with the proper steam making operation of the boiler.
4. The amount of water most desirable for 40 circulation.
5. The degree of pressure drop required to insure one path flow and/or semi-unidirectional flow of the working fluid.
6. The size of orifice, or pressure drop device 45 desirable to avoid clogging.
7. Mechanical and boiler cleaning considerations.
8. The question as to whether it is better to 50 operate a portion of the steam generating section with the so-called full tube condition, or with less than sufficient to fill the tubes condition.

In one of its aspects my invention is a high speed steam generator whose water walls in the 55 radiant heat releasing and receiving area, namely the combustion zone, and whole steam generating tubes exposed to convection heat transfer in the convection heat zone, will not give an undue amount of surging of steam and water travelling back and forth in the tubes but will have positive semi-unidirectional flow of water in each wall tube, at all times, regardless of combustion conditions in the firebox or the size or movement of large steam bubbles shifting from side 60 to side in individual water wall tubes, or group of water wall tubes, up to the maximum rate of combustion at which the steam boiler is designed to operate.

In the further aspect, my invention seeks to 70 take this steam made at high speeds, then by means of a high speed steam engine, (preferably a steam turbine operating under high temperatures and pressures), convert this steam into power in a rapidly operating steam power plant 75 where all auxiliaries are functioning at maximum

speeds, and are closely coordinated and controlled to produce power in large quantities with the minimum in size, weight and cost of power producing equipment.

The steam and water collected in header 36 5 discharges by way of conduits 37 (Figure 2) into water level cylinder 8 for maintaining a water level in the system, furnishing reserve power, and insuring water supply to the circulating pumps. The steam is separated from the water in the 10 cylinder 8, and passes through the main high pressure steam line 9, having main control valve 61 therein for controlling the steam to the main turbine 10. Furthermore, a pipe line 7 extends from the upper end of cylinder 8 to auxiliary 15 steam turbine 6 having control valve 42 therein for controlling the drive of auxiliary turbine 6, which drives the air super-charger fan 5, fuel oil pump 27, boiler feed pump 17 and boiler circu- 20 lating pump 26.

The main exhaust lead 10A from the main turbine extends from the latter to the main condenser 11. Pipe 12 represents the inlet for circulating cooling water to the main condenser 11, and pipe 13 is the outlet pipe therefor. Pipe 14 is 25 the condensate water discharge from the main condenser 11 to the main feed tank 15 having feed water inlet 46 and control valve 43 therefor. Vent 47 is associated with the feed water tank, and suction lead 29 extends from the latter to the 30 condensate pump 16 or feed pump 17. 18 is a discharge pipe connecting feed pump 17 with the water level cylinder 8; 19A is a by pass line for by-passing feed water around the feed pump 17 through water level regulator valve 19, for controlling the water level in the system; and 20 is 35 a feed stop and check valve on the feed pump discharge lead 18 for stopping and checking the feed of water into the system.

Associated with the cylinder 8 is a safety valve 40 21 for the boiler at the top of the cylinder, and a blow-off valve 22 at the bottom thereof. The cylinder has a gauge glass 23, and an automatic water level regulator 24A from which extends a pipe 25 to the control valve 19.

The main steam generator circulating pump is 45 represented at 26. The suction line for pump 26 is connected with the water level cylinder 8, through pipe 31, and the discharge pipe 32 of this pump extends therefrom to the inlet header 33. 50 The main circulating pump is fitted with a by pass 45 therearound, to control the quantity of water which is circulated by means of control valve 44 in this by-pass.

The fuel oil tank is represented at 38 with 55 its suction line 39, vent 50, filling line 48, and control valve therefor, 49, and burner by-pass return oil discharge lead 61A. Opening into the fuel line into the burner is a pipe having a control valve therein 61D for introducing starting oil into 60 the burner, and 61E is a valve for shutting off the oil normally used in the operation of the plant, while using the starting fuel oil. Pipe 28, constituting the exhaust lead from the auxiliary turbine 6, opens into the main turbine exhaust 65 lead 10A.

Figures 5 and 6 show schematically arrangements similar to that shown in Figure 1. In Figure 5, the fuel air mixture and burned gases 70 travel substantially parallel to the flow of water in the steam generator tubes fitted with pressure drop devices 35 at intermediate points of the length thereof, in accordance with the present invention. In Figure 6, the gases travel in a 75

countercurrent direction to the direction of the flow of water.

Figures 7 and 8 show spiral sets of water wall generator tubes fitted with pressure drop devices 35 with each set having an individual circulating pump 26^A, 26^B, and 26^C.

In Figure 9 is shown a complete high speed power plant embodying the highly efficient boiler generating superheated steam. The circulating 10 system for water and fuel resembles that illustrated in Figure 1, and a detailed description of the duplicate parts will not be set forth below.

The central combustion chamber 106, as shown, has steam generator tubes 34 therein through 15 which water is circulated from inlet header 33 to outlet header 36. The steam and water produced in accordance with the present invention, is discharged into the tube 37 at the end of the boiler opposite the burner, and thence to the 20 water level cylinder 8. Tube 51 extends from the upper end of the cylinder 8 at 51^A, to deliver saturated steam therefrom to the superheater tubes coiled around the interior of the combustion chamber which are shielded by the 25 steam generator tubes 34.

In addition to the steam generating tubes 34 in the combustion chamber, auxiliary steam generating tubes 52 are coiled in annular passage 108, formed on the outside of the combustion chamber 106, and confined by an external wall 202, which forms a tapered passage extending from the inlet thereof at 107, to the outlet thereof, at 109. The combustion gases travel upwardly to the top end of the chamber 106 and then pass 35 through passage 107 downwardly, through the passage 108, giving up the heat contained therein to the steam-generating tubes 52. The tubes 52 may be supplied with circulating water from the main steam generator circulating pump 26 and 40 these tubes discharge the steam and water therein into the water level cylinder at 52^A. These tubes 52 in the convection passage may be provided with fins 52^B and 52^C, extending in parallel to the axis of the tubes, as shown in Figures 45 14, 15 and 16, for the purpose of more effectively extracting the heat from the combustion gases.

In addition to the steam generating tubes 34 and 52 described above, tubes 55 may be provided for protecting the combustion chamber inlet wall 50 205, which receives water from the inlet header 33 and discharge water and/or steam to the collecting header 36.

The combustion gases passing downwardly through the convection passage 108, pass through 55 the exits 109^A into a series of spirally disposed burnt gas passages 110. These spiral passages terminate near the top of the boiler into a passage 111, which open into a common outlet passage 112, to which is connected the tangential 60 stack outlet passage 113 opening into the atmosphere.

The incoming air used for combustion which is commingled with the fuel supplied by burner 2 in the throat 104, is admitted to the throat 65 through openings 103, after passing in heat-exchanging relationship with the burnt gas passages 110. The air is supplied from the air supercharger 60 (Figure 12), to the pipe 100 opening tangentially into the casing of the boiler 201. 70 This casing forms in conjunction with the walls 203 forming the passages 110, a plurality of spiral air-preheater passages 101, which travel downwardly in Figures 9 and 11 towards the air inlets 103. The area of the spiral air-preheater passages increase from the air inlets to the air out-

lets, while the burnt gas passages 110 decrease from the inlets to the outlets thereof, for the reasons set forth below.

In the boilers shown in Figures 9 and 11, an inspection and ignition port 105 is provided covered by detachable closure 212.

In the modification of the invention illustrated in Figure 17, the burner is disposed at the upper end of the boiler and coiled steam generating tubes 34 are utilized. An additional refinement 10 of this boiler over the one illustrated in Figures 9 and 11 may be found in the provision of coiled economizer tubes disposed in a tapered passage 109^B formed between walls 202 and 218 into which the burnt gases pass from the convection steam 15 generating portion prior to the spiralled burnt gas passages 110, for the purpose of giving up more of their heat content.

The improved design of my boiler embodiments described above are predicated upon the theories 20 and features set forth below.

I have found that, with my high speed steam generators with supercharged combustion, a large amount of power can be produced from a small combustion chamber. High initial temperatures are produced in said combustion chamber sending gases of high initial temperature to the convection surfaces. To reduce the temperature of the convection gases, it is general practice to complete the superheating of the steam, 30 the generation of the steam by the convection gases and the preheating of the air by the convection gases.

In order to keep my units in a compact form all convection surfaces must be grouped around 35 my comparatively small combustion chamber. It is very desirable to obtain longer gas travel or a type of gas travel over the surface which produces a more disruptive effect or upsetting of the gas than is obtained by present methods with 40 cross flow or parallel flow.

In this invention I show the use of spiral flow made by forming spiral passages around my combustion chamber with tubing or metal or both, said passages being tapered to obtain the proper 45 gas velocities as the gas changes in volume and density in its flow throughout the spiral passages.

This arrangement gives a long travel for the gas mainly in parallel spiral flow and permits the using of very high gas velocities considerably 50 above the beginning of the critical condition of flow, with low draft loss.

Where the heat effects are very high the passage may be lined with tubing adjacent to each other eliminating the need of a close contact of 55 the tubing with the metal walls and a carefully designed spacing apart of the tubing on these walls to meet the given heat load.

Where the heat effects are low and the spacing of the tubing is merely a question of obtaining 60 the maximum transfer results to the entire tube surface, metal spiral passages may be used and the tubes spaced only in reference to the heat transfer to the tube surface.

It is a general characteristic of my circumferential heat exchanging passages for such passages, to taper from a ring shaped inlet opening of wider width to a ring shaped outlet opening to a narrower width, and where tubes or other heat exchange elements occupy such passages in 70 spiral arrangement, the distance between such tubes (as they spiral in the wider circumferential portion of the passage to the narrower circumferential portion of the passage), is, in accordance with my invention, closer, the tubes are 75

progressively more closely packed, or lay nearer together.

The reason for this more closely packed arrangement of the tubes is, so that the heat is withdrawn from the burnt gases, releasing their heat to the cooler walls of the tubes containing rapidly flowing boiler working fluids (as rapidly flowing air, if it is intake air, receiving the heat, i. e., in the air preheater), the velocity of the flow of the heating gases is not slowed down, due to the diminishing density of the hot gas on account of the removal of its heat, but that by diminishing the volume of the circumferential space and circumferential spiral space through which the gases flow, as those gases flow from the hotter zone to a cooler zone, the high velocity of the gases will be kept up, or maintained, this high velocity assisting materially in, and increasing the effectiveness and efficiency of, the heat transfer taking place between the hot burned gases and the working fluid or the air, on the other side of the walls receiving heat from said hot burned gases.

In my structural design, my air preheater passages, both for air flow 101 and burnt gas flow 110, are spiral, curved around the boiler and tapered, the taper of each of the passages for the burnt gas, decreasing in area with the decrease in volume and change in density, and the passages for the air increasing in area with the increase in air volume and change in density, so that the proper velocity of air and burnt gas is maintained throughout the length of these passages as the gases change in volume and density, and travel in counterflow to each other.

My economizer spiral tapered passage 109B (Fig. 17) for the convection burnt gases and my spiral tapered convection steam generator passage 108, for the convection burnt gases are also tapered to maintain the proper velocity of burnt gases throughout their length as the convection burnt gas changes in volume and density in its travel through said passages.

Air coming from the tangential air discharge lead 100 of the supercharger fan 5 into the circular air inlet passage 100A to the air preheater is given a whirling motion.

As the air passes from the circular air inlet passage 100A into the air preheater spiral tapered air passages 101, it is given a further whirling motion in the same direction by having the spiral tapered air passages 101 spiralled in the proper direction to accomplish this purpose.

The air leaving the spiral tapered air preheater air passages passes into the burner circular entrance air passage 102 still whirling and into the burner entrance 103.

From the burner entrance 103, the heated air still whirling enters the burner throat 104, and then into the combustion chamber 106 where it mixes with the fuel, burns, and forms the burnt gases.

The spiral of the waterwall tubing 34 and the superheater tubing 51 in the combustion chamber 106 is so arranged that the air and burnt gases continue to whirl in the same direction as the gases travel in the combustion chamber 106 toward the outlet end into the combustion chamber circular gas inlet passage 107 and then into the spiral tapered convection steam generating burnt gas passage 108.

The spiral of the convection steam generator tubing 52 is wound opposite to that of the waterwall 34 and superheater tubing 51, so that the burnt gases travelling in said passage 108 from

the combustion chamber 106 continue to whirl in the same direction.

The spiral of the economizer tubing 53 is wound opposite to that of the spiral convection steam generating tubing 52, so that the burnt gases, whirling from spiral tapered convection steam generating passage 108 into the circular outlet convection steam generating burnt gas passage 109A and then into the spiral tapered economizer burnt gas passage 109B, will continue to whirl in the same direction in said passage 109B, then passing into the circular outlet economizer burnt gas passage 109C and then into the spiral tapered air preheater burnt gas passages 110.

From the spiral tapered air preheater burnt gas passage 110 the burnt gases travel through the exit connectors 111 of the spiral tapered air preheater burnt gas passages 110 to the circular exit convection burnt gas passage 112 and then through the tangential stack outlet passage 113 to the atmosphere.

I streamline many of my fluid passages ways throughout the boiler structure, especially at the turns and at changes in direction of the flow of gases, high velocity of gas flow can be maintained throughout the system with small draft loss at these points leaving the main draft loss available for high speed travel over the heating surfaces where such loss is more than repaid by the increased heat transfer rates obtained.

In streamlining the steam generator, I use a smooth curved turn 219, where the casing 205, meets the water wall casing 206, to guide any gas, flowing radially from the burner to the sides.

At the outlet end of the combustion chamber, I use a circular conical nose, 207, projecting toward the interior of the combustion chamber at the central portion of the top casing to spread and guide the high velocity gases toward the outer circumference of the combustion chamber at this point; and where the gases are to be guided into the entrance of the convection heating surface.

The conical central portion 207, in the top casing is followed by a portion depressed in said casing, relative to the interior of the combustion chamber and this portion in turn is followed by a smooth curved turning of the top casing, leading to the convection gas passage wall 202, so that radially from the central portion of the top casing to the circumference the said casing is first conical, then depressed, then curved, relative to the interior of the combustion chamber, to guide the gases in a smooth streamlined flow from the center of the combustion chamber to the entrance to the convection heating surface, including the turn into the convection heating passage 108.

As the whirling burnt gases leave the convection heating passage 108, they enter the circular outlet curved convection steam generating burnt gas passage 109A and are turned smoothly into the spiral tapered economizer burnt gas passage 109B.

As the whirling burnt gases leave the spiral tapered economizer burnt gas passage 109B they enter the circular outlet curved economizer burnt gas passage 109C (Fig. 17) and are turned smoothly into the air preheater spiral tapered burnt gas passages 110.

As the whirling burnt gases leave the air preheater spiral tapered burnt gas passages they pass through the exit connections 111 of said passages 110 into the circular exit convection burnt gas passage 112 into and through the tangential stack outlet.

The constituent parts of the boiler in accordance with my present invention are preferably constructed of non-corrosive metal alloys. With such a construction it is necessary to properly 5 and thoroughly protect the metal walls from exposure to a too high effect from the radiant gases. This is accomplished by placing cooling and protecting cooling surfaces in front of and in contact with the metal walls.

10 If the points of contact of the tube cooling surface to the combustion chamber wall are sufficiently close together and if there is a proper degree of shielding of the metal walls from radiant heat action, the alloy metal can withstand 15 any designed rate of heat release.

Due to the high heat conductivity of the metal transferring heat received immediately to adjacent cooling tubes, it is not necessary to put a solid bank of tubes in front of and adjacent to 20 it. The degree of spacing of the protecting and cooling surface depends on the designed heat load for which the steam generating apparatus is to be used.

If the tubes are placed unnecessarily close to 25 each other the radiant heat will act not only on a small part of the tube surface, resulting in lower heat transfer per unit of surface of the tubes. The tubes should be spaced as far apart as is practicable without allowing the metal walls 30 to become overheated.

I have found that it is necessary to protect the ends of the combustion chamber metal wall as well as the sides. Thus in Fig. 9, steam generating tubes 37 are provided adjacent the end 35 wall of the combustion chamber opposite the burner receiving water from the outlet header 36 and opening into the upper end of water level cylinder 8, where the steam generated therein is separated from the water. Tubes 55 protect the 40 opposite end of the combustion chamber.

In many cases of designing it is undesirable to cover the ends of the combustion chamber with separate tubes.

In many other cases, especially as the size of 45 the unit increases, a single tube to cover both ends and the sides would be too long. Further as the size increases, the volume of steam in the waterwall tube increases and therefore the velocity makes it necessary to use large diameter tubes 50 where single tubes of great length are used otherwise, the resulting very high velocity with the long, small diameter tube would give large and undesirable pressure drops. A large diameter tube greatly increases the weight per square foot of 55 the heating surface. As a result it is generally of advantage to use multiple small diameter tubes of moderate length for the combustion chamber of my high speed and light weight steam generators, both for the superheater and water- 60 wall, and it is also generally of advantage to have said tubes assist in covering the ends of the combustion chamber as well as the sides.

In my present invention I expose only part of my superheating surface formed by tubes 51 to 65 direct radiant heat action. Therefore, I call this type of superheater a semi-radiant superheater, as it is different from present types of radiant superheaters in the combustion chamber. This term "semi-radiant" connotes a superheater in 70 the combustion chamber which has a part of its surface, but not all of its surface, exposed to radiant heat action.

I have found it in some cases necessary in my 75 spiral heat transferring passages to devise heat exchanging tubular elements for holding liquids

and/or vapors and gases, said elements having fins disposed lengthwise the tube, the fins being in certain instances integral with the tubes and in certain other cases attached firmly to the tubes with a good heat exchanging bond between the fin and the tubes.

I have had to invent ways of making such tubes, for example, and ways of placing these longitudinally finned tubes packed progressively close in my tapered circumferential heat 10 exchanging passages.

Fig. 20 indicates the method of manufacturing tubes with integral fins. Shorter, thick fins as designated by the dot and dash line in the figure and formed when the tubes are either drawn 15 or extruded are later subjected to a rolling action wherein each fin is rolled, thinner and longer by a pair of rolls which works the metal into the final desired thin section. In carrying on this later rolling operation to thin and lengthen the 20 depth of the individual fins on the tube, I prefer to fill the interior of my tube, while this rolling action is taking place, with a solid or fluid, (either 25 pneumatic or hydraulic) filler.

It is within the scope of my invention to solder, 30 weld, braze and/or otherwise fasten my longitudinal fins in position on my tubes. It is also the spirit of my invention to employ tubes with fins having a gradual spiral placement on my tube 35 so that as the tube is laid spirally in the tapered 40 passage and progressively packed more closely together to have the fins twist the air and/or burning gases in receiving as these burning gases along and adjacent to the outside of said tubes.

All that has been written above about the placing 45 of longitudinally thin tubes, their manufacture and so forth is particularly appropriate because long spiral fins will function almost as well 50 for my heat transferring work as long fins that are substantially parallel to the center line of the tubes, providing the pitch of the spiral fin in its screw form is greater than three times the outside 55 diameter of the spiral measured as the distance across the metal tube mid-way between two fins to the same point on the other side of the 60 tube.

It will be noted that in the embodiment illustrated in Figure 17 I protect my combustion chamber wall with a coiled waterwall, the coiled waterwall also protecting the superheater tubes 50 coiled adjacent to the combustion chamber. It has been shown advisable to sometimes use the straight tubes of the water wall to hold in place the coiled tubes of the superheater and although such fastening means is not shown on my drawings it is well within the scope of my invention to employ holding devices for the superheater coil whereby said coil is sustained and/or held in position by my waterwall tubes.

What I claim is:

1. In a power plant, the combination comprising 65 a boiler, a turbine receiving steam from said boiler, a condenser attached to said turbine receiving and condensing steam issuing from said turbine, another turbine attached to and receiving steam from said boiler, a feed pump connected to said condenser and said boiler serving said boiler with feed water, said feed pump driven by said second turbine, a water and steam separating chamber connected to said boiler, a circulating pump constantly circulating and recirculating water from said boiler to and through 70 said water and steam separating chamber and conduits connecting said steam and water sep- 75

arating chamber and both of said turbines, said conduits serving said turbines with steam.

2. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, coiled tubes in said combustion chamber, spirally coiled tubes in said annular passage arranged to form helical gas passages adapted to be traversed by the combustion gases passing through said combustion chamber towards the wide portion of said annular passage and thence towards the narrow portion thereof, a helical wall forming at least one spiral passage connected with the outlet of said tapered passage adapted to conduct the burnt gases from the boiler, and at least one spiral air passage formed adjacent said burnt gas passage in heat-exchanging relationship therewith adapted to conduct the incoming combustion air in a counter-current direction to the burnt gases for mixture with the fuel issuing from the burner.

3. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, spirally coiled steam superheating tubes arranged in said combustion chamber, steam generating tubes in front of said superheater tubes and shielding said last-mentioned tubes at least partially from the radiant gases, spirally coiled water-conducting tubes in said tapered annular passage arranged to form helical gas passages adapted to be traversed by the combustion gases passing from said combustion chamber towards the narrow portion of said tapered passage, helical walls forming a plurality of spiral passages connected with the outlet of said tapered passage adapted to conduct the burnt gases from the boiler, and a plurality of spiral air passages formed adjacent said burnt gas passages in heat-exchanging relationship therewith adapted to conduct the incoming combustion air in a counter-current direction to the burnt gases for mixture with the fuel issuing from the burner.

4. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, coiled tubes in said combustion chamber, spirally coiled steam-generating tubes in said annular passage arranged to form helical gas passages adapted to be traversed by the combustion gases passing through said combustion chamber towards the wide portion of said annular passage and thence towards the narrow portion thereof, helical walls forming a plurality of spiral passages connected with the outlet of said tapered passages adapted to conduct the burnt gases from the boiler, and a plurality of spiral air passages formed adjacent said burnt gas passages in heat-exchanging re-

lationship therewith adapted to conduct the incoming combustion air in a counter-current direction to the burnt gases for mixture with the fuel issuing from the burner.

5. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, coiled tubes in said combustion chamber, spirally coiled steam-generating tubes in said annular passage arranged to form helical gas passages adapted to be traversed by the combustion gases passing through said combustion chamber towards the wide portion of said annular passage and thence towards the narrow portion thereof, a second lateral wall outside of said first lateral wall and arranged to define a second tapered annular passage on the outside of said first tapered passage, an end wall connected with said second lateral wall for directing the gases from said first passage to the wide portion of said second passage, spirally coiled water-conducting tubes in said last mentioned passage arranged in helically divided gas passages adapted to be traversed by the combustion gases passing from said first passage towards the narrow portion of said second tapered passage, a helical wall forming at least one spiral conduit attached to the outlet of said second tapered passage adapted to conduct the burnt gases from the boiler, and at least one spiral air conduit formed adjacent said burnt gas conduit in heat-exchanging relationship therewith.

6. The combination set forth in claim 2 wherein the spiral passage for the burnt gases decreases in cross-sectional area from the inlet to the outlet thereof.

7. The combination set forth in claim 2, wherein in the spiral passage for the air increases in cross-sectional area from the inlet to the outlet thereof.

8. The combination set forth in claim 2 wherein in the spiral passage for the burnt gases decreases in cross-sectional area from the inlet to the outlet thereof, and the spiral passage for the air increases in cross-sectional area from the inlet to the outlet thereof.

9. The combination set forth in claim 2, wherein in the spiral air passage is formed by a metallic casing surrounding the helical wall forming the spiral passage for the burnt gases.

10. The combination set forth in claim 2 wherein the spirally coiled tubes in said annular passage are provided with fins for facilitating the formation of the helical gas passages and the transfer of the heat content of the gaseous medium.

11. The combination set forth in claim 2 wherein the spirally coiled tubes in said annular passage are provided with fins extending in parallel to the axes of the tubes for facilitating the formation of the helical gas passages and the transfer of the heat content from the gaseous medium.

12. The combination set forth in claim 2 wherein the spirally coiled tubes in said annular passage are provided with fins extending helically with respect to the axes of the tubes for controlling the travel of the gases through the helical gas passages and improving the transfer of the heat content therefrom.

13. The combination set forth in claim 4 wherein the helical walls forming the spiral passages for the burnt gases are provided with fins for facilitating the transfer of the heat content therefrom to the incoming air.
14. The combination set forth in claim 2 wherein the spirally coiled tubes in said tapered annular passage are more closely packed as they approach the narrow outlet end of said passage from the wider inlet end thereof.
15. The combination set forth in claim 2 wherein the helical gas passages formed by the spirally coiled tubes in said annular passage decrease in cross-sectional area from the inlet end to the outlet end thereof.
16. The combination set forth in claim 5 wherein the helical gas passages formed by the spirally coiled tubes in the first tapered annular passage and the helically divided gas passages in the second tapered annular passage decrease in cross-sectional area from the inlet end to the outlet end of the respective helical passages.
17. The combination set forth in claim 2 wherein the spirally coiled tubes in said tapered annular passage are spiraled oppositely to the coiled tubes in the combustion chamber whereby the gas currents whirl in the same direction in consequence of the reversal of the path of flow thereof in passing from said combustion chamber to said annular passage.
18. The combination set forth in claim 5 wherein the spirally coiled tubes in said first tapered annular passage are spiraled oppositely to the coiled tubes in the combustion chamber whereby the gas currents whirl in the same direction in consequence of the reversal of the path of flow thereof in passing from said combustion chamber to said annular passage, and the water conducting tubes in the second tapered annular passage are spiraled oppositely to the coiled tubes in said first annular passage, whereby the gas currents whirl in the same direction in consequence of the reversal of the path of flow thereof in passing from said first tapered annular passage to said second tapered annular passage.
19. The combination set forth in claim 4 wherein the steam-generating tubes in said combustion chamber and tapered annular passage are provided with pressure drop devices at intermediate portions of their length.
20. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral and combustion chamber wall arranged to define a tapered annular passage on the outside of said combustion chamber, coiled tubes in said combustion chamber, and spirally coiled tubes in said annular passage arranged to form helical gas passages adapted to be traversed by the combustion gases passing through said combustion chamber towards the wide portion of said annular passage and thence towards the narrow portion thereof.
21. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, spirally coiled tubes in said annular passage arranged to form helical gas passages adapted to be traversed by the combustion gases passing through said combustion chamber towards the wide portion of said annular passage and thence towards the narrow portion thereof.
22. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, coiled tubes in said combustion chamber, and spirally coiled steam-generating tubes in said annular passage arranged to form helical gas passages adapted to be traversed by the combustion gases passing through said combustion chamber towards the wide portion of said annular passage and thence towards the narrow portion thereof.
23. A steam generator comprising a substantially cylindrical open-ended combustion chamber, a burner at one end thereof and an end wall at the other end thereof displaced from the open end of said combustion chamber, a lateral wall outside of the wall of said combustion chamber, said lateral wall and combustion chamber wall arranged to define a tapered annular passage on the outside of said combustion chamber, coiled tubes in said combustion chamber, spirally coiled steam-generating tubes in said annular passage arranged to form helical gas passages adapted to be traversed by the combustion gases passing through said combustion chamber towards the wide portion of said annular passage and thence towards the narrow portion thereof.
24. The combination set forth in claim 20 wherein the spirally coiled tubes in said annular passage are provided with fins for facilitating the formation of the helical gas passages and the transfer of the heat content of the gaseous medium.
25. The combination set forth in claim 20 wherein the spirally coiled tubes in said tapered annular passage are more closely packed as they approach the narrow outlet end of said passage from the wider inlet end thereof.
26. The combination set forth in claim 20 wherein the helical gas passages formed by the spirally coiled tubes in said annular passage decrease in cross-sectional area from the inlet end to the outlet end thereof.
27. The combination set forth in claim 23 wherein the helical gas passages formed by the spirally coiled tubes in the first tapered annular passage and the helically divided gas passages in the second tapered annular passage decrease in

cross sectional area from the inlet end to the outlet end of the respective helical passages.

28. The combination set forth in claim 20 wherein the spirally coiled tubes in said tapered annular passage are spiralled oppositely to the coiled tubes in the combustion chamber, whereby the gas currents whirl in the same direction in consequence of the reversal of the path of flow thereof in passing from said combustion chamber to said annular passage.

29. The combination set forth in claim 23 wherein the spirally coiled tubes in said first tapered annular passage are spiralled oppositely to the coiled tubes in the combustion chamber whereby the gas currents whirl in the same direction in consequence of the reversal of the path of flow thereof in passing from said combustion chamber to said annular passage, and the water conducting tubes in the second tapered annular passage are spiralled oppositely to the coiled tubes in said first annular passage, whereby the gas currents whirl in the same direction in consequence of the reversal of the path of flow thereof

in passing from said first tapered annular passage to said second tapered annular passage.

30. The combination set forth in claim 21 wherein the steam-generating tubes in said combustion chamber and tapered annular passage 5 are provided with pressure drop devices at intermediate portions of their length.

31. A steam generator comprising a substantially cylindrical open-ended combustion chamber, a burner at one end thereof and an end wall 10 at the other end thereof displaced from the open end of said combustion chamber, a lateral wall outside of the wall of said combustion chamber, said lateral and combustion chamber wall arranged to define a tapered annular passage on 15 the outside of said combustion chamber, coiled tubes in said combustion chamber, and spirally coiled tubes in said annular passage arranged in helically directed gas passages adapted to be traversed by the combustion gases passing 20 through said combustion chamber towards the wide portion of said annular passage and thence towards the narrow portion thereof.

WALTER DOUGLAS LA MONT.
